CARBURETOR

Elmer Olson, Rochester, N. Y., assignor to General Motors Corporation, Detroit, Mich., a corporation of Delaware

Original application August 9, 1949, Serial No. 109,347, now Patent No. 2,694,560, dated November 16, 1954. Divided and this application July 21, 1954, Serial No. 444,731

2 Claims. (Cl. 261—34)

This invention relates to carburetors for internal combustion engines, most particularly those for automotive use, and is directed specifically to an improvement in the pump mechanism provided to supply additional fuel during acceleration to prevent leaning of the mixture when the throttle is opened to increase speed.

It has been found that with highly volatile fuels such as are now in common use, the carburetor will, at times, get hot enough in hot weather, after the engine is stopped, to vaporize fuel in the cylinder of the accelerator pump below the piston therein and the formation of this vapor is effective to force solid fuel out of the pump-delivery passage and into the mixture passage. This creates an undesirable situation and the effect is very much like that produced by "percolation" in the fuel supply passages. If it continues long enough, the fuel level in the supply chamber might be considerably reduced, in fact, the chamber might be completely emptied. This would obviously make subsequent starting difficult, as starting could not be accomplished until the fuel supply chamber was re-filled. This could only be done by prolonged cranking of the engine, which is obviously objectionable for various reasons.

It is accordingly the primary object of the present invention to provide means for permitting the escape of fuel vapor from the bottom of the accelerating pump cylinder when the engine is not in operation, so as to prevent the forcing of fuel from such cylinder into the mixture passage.

Further objects and advantages of the present invention will be apparent from the following description, reference being had to the accompanying drawings wherein a preferred embodiment of the present invention is clearly shown.

In the drawings:

Figure 1 is a vertical section through the carburetor and accelerator pump;

Figure 2 is a detail section showing the fuel delivery passage leading from the pump cylinder to the mixture passage; and

Figure 3 is a detail view showing the passage connecting the pump cylinder with the fuel supply chamber.

The present invention is shown as embodied in a carburetor such as illustrated in application S. N. 109,347 of Elmer Olson, filed August 9, 1949, now Pat. No. 2,694,560, issued November 16, 1954, of which the present application is a division. Since the invention to which this particular application relates involves the construction of the accelerator pump only, the structure of the carburetor, other than the pump mechanism, will be only briefly described.

The carburetor, which is of down-draft type, comprises three separate castings 2, 4 and 6, positioned one above the other. The casting 2, which constitutes the air inlet, is supported on top of the casting 4 in which the fuel chamber and the mixing chamber are positioned, and the casting 4 is supported on the casting 6 in which the throttle valve which controls the quantity of fuel mix-

2

ture supplied to the engine is rotatably mounted. Suitable gaskets are positioned between the castings 2 and 4, 4 and 6. The air inlet passage is indicated at 8 and this communicates with the mixing chamber 10 in casting 4, from which combustible mixture is delivered to the outlet passage 12 in casting 6.

The admission of air through the passage 8 is controlled by a manually controlled but unbalanced choke valve 14, secured to a shaft which is rotatably mounted in the casting 2, and the quantity of combustible mixture supplied to the engine is controlled by a throttle valve 16 secured to shaft 18 rotatably mounted in casting 6.

The operating connections for the throttle and choke valves constitute no part of the present invention and can be of any suitable construction. However, some of the connections are shown in Fig. 1 and are, therefore, very briefly described hereinafter. The throttle is operated by the arm 20 secured to one end of shaft 18 and connected by an operating connection (not shown) to the usual accelerator pedal. The choke valve is operated by an arm 22, through a manual connection (not shown) extending to an operating member on the instrument panel. The arm 22 is movable on the choke valve shaft and the shaft is operated through the medium of a torsion spring 24 in the manner described in the previously mentioned parent application. The arm 22 has a cam surface formed thereon which engages a laterally extending ear 26 integral with a lever 28, pivotally mounted on a boss 30 and engaged by a torsion spring 32, which is a return spring. At the lower end of lever 28 there is a projecting ear 34 which is engaged by an adjustable screw 36 on the operating arm 20 to determine the normal idle position of the throttle and also is moved by ear 34, when arm 22 is actuated to fully close the choke, so as to open the throttle slightly to effect faster than normal idling when the choke is fully closed at low temperatures.

Fuel is supplied to a chamber 40 in the casting 4 through a conduit 42 connecting with a passage 44 in casting 2. A passage 46 in a nipple 48 connects passage 44 with chamber 40, and flow through the passage 46 is controlled by a valve 50 which rests on an arm 52 operated by the usual float (not shown), in the conventional manner to maintain a constant fuel level in chamber 40.

Fuel flows from the chamber 40 to main and idling fuel inlets through a metering plug 54 to a vertical passage 56 which connects at its upper end with a horizontal passage 58 formed in a tubular part of the casting 2 which extends across the mixture passage. Fuel flows from this passage through a restricted nozzle 62 which terminates in a small venturi tube 64 discharging into a large venturi tube 66 formed by the wall of the mixing chamber.

The passage 58 extends all the way across the mixing chamber and at the left end connects with a vertical passage 68 in the casting 4, which leads to the idling fuel inlet (not shown). A plurality of openings 70 admit air to the passage 58 to form an emulsion of fuel and air therein.

The arrangement of fuel passages above-described is the same as that shown in the above-mentioned parent application and since the specific arrangement of such passages forms no part of the present invention, no more detailed description is necessary herein.

A pump is provided which is operated by a connection extending to the throttle operating mechanism, and which supplies additional fuel whenever the throttle is moved toward open position relatively rapidly, for the purpose of providing a mixture rich enough to bring about satisfactory operation of the engine upon acceleration thereof.

Whenever the throttle is opened relatively rapidly, the increase in air flow is more rapid than the increase in fuel flow from the main nozzle 62. This tends to lean the mixture, which would cause unsatisfactory engine operation and the pump supplies additional fuel to offset this leaning effect.

This pump includes a cylinder 72 formed in the casting 4 and communicating with a space 74 of generally cylindrical form in the casting 2 and positioned immediately above the cylinder 72 when the device is assembled. A piston 76 is slideable in the cylinder 72 and is secured to a piston rod 78 which extends upwardly from the piston. The piston is operated by a connection operable by the throttle operating arm 20 which includes a link 80 pivotally connected to the arm 20 and to a rod 82 slideable in a passage in the casting 4 and having a horizontal extension 84 at its upper end. This extension is received in a slot 86 in the upper end of the piston rod 78 so that it can move relatively to said rod. The extension 84 engages a washer 90 which engages the upper end of a spring positioned between the washer and the top of piston 76. A spring 94 is positioned in the cylinder 72 between the piston and the bottom of the cylinder and normally holds the piston in its upper position, as shown in the drawings.

Fuel is supplied to the space in cylinder 72 below the piston through a passage 96, connecting this space with the fuel chamber 40. A screen 98 is positioned in the intake end of this passage and a check valve 100 prevents fuel being forced out through such passage on the operative stroke of the pump piston. A fuel delivery passage also connects with the cylinder 72 below the piston, this being the passage 102 in casting 4, as shown in Fig. 2, which connects with passage 104 in the casing 2, that supplies fuel to a nozzle 106 which extends at an angle and downwardly into the mixing chamber.

Adjacent its point of connection with passage 104 the passage 102 is enlarged as indicated at 108 to form a seat for a ball check valve 110, which is normally held seated by a spring 112, but which is forced off its seat upon the operative stroke of the pump piston. The spring 112 is received between the ball and a plug 114 which limits the upward movement of the ball and has a passage 116 to permit passage of fuel therethrough. The spring is of sufficient strength to hold the ball seated under normal conditions, when the pump is not in operation, so that no fuel will be normally drawn from the pump into the mixing chamber by the effect of suction on the delivery nozzle 106.

When the throttle is opened, the element 84 is moved downwardly. This will normally compress the spring 92 to some extent before the piston starts to move downwardly. The piston will then continue to move downward after movement of the throttle stops, so that normally, the action of the pump is somewhat delayed and does not begin until the compression of spring 92 is sufficient to cause the force exerted by spring to overcome the opposing force exerted by spring 94 and the resistance of the piston to movement. If the throttle is moved very rapidly and far enough, the part 84 may be moved into engagement with the bottom of slot 86 and the piston would be positively moved by its operating rod 82 during a part of its movement and would then move further as spring 92 expands after the throttle stops.

Since the bottom of the pump cylinder is quite close to the manifold, it is likely to get quite hot after the engine stops, particularly in hot weather, in fact, hot enough to vaporize the fuel standing in the cylinder below the piston. If there was no means for this vapor to escape, the pressure created thereby would force liquid fuel out through the pump delivery passage and nozzle 106 into the mixing chamber. The bottom of the cylinder would then fill up again with fuel and the process described might be repeated for a considerable period of time, until

the temperature dropped sufficiently for vaporization of fuel to cease. This action might be very objectionable and, indeed, might empty the chamber 40 of fuel.

In order to prevent the occurrence described, means are provided to permit escape of fuel vapor from the space in the pump cylinder below the piston, so that no pressure will be created on the fuel therein, tending to force it into the mixing chamber. To this end, the piston 76 has an axial passage 120 therethrough which connects with a passage 122 in the piston rod 78 which leads to the space above the piston which is in registry with the space 74 and a vent tube 124 connects this space with the air intake. Any vapor escaping from the pump cylinder through passage 120 will eventually be discharged into the air inlet of the carburetor.

The passage 120 is closed on the operative stroke of the pump piston by a ball check valve 126 which is moved upwardly to close the bottom of passage 120 by pressure of fuel on the ball, but normally when the piston is not moving, the ball rests in the position shown in Fig. 1, on top of a short tube 128 and slightly spaced from the bottom of passage 120 so that fuel vapor can escape through the passage between the ball and the bottom of the piston, into passage 120 and eventually into the air inlet. The tube 128 is supported by four spaced ribs 130 connecting the tube and piston and the end of the tube is so positioned with respect to the piston that when the ball valve 126 is seated on top of the tube, as shown in Fig. 1, there is sufficient space between the ball and the bottom of the piston for any vapor which may form in the cylinder to pass between the ball and the piston and escape through passage 120. Obviously, as soon as the piston begins to move down on its operative stroke, the ball will seat against the end of passage 120 and prevent any fuel from passing through such passage.

While the embodiment of the present invention as herein disclosed constitutes a preferred form, it is to be understood that other forms might be adopted.

What is claimed is as follows:

1. In a carburetor having a mixture passage, a throttle controlling the flow of combustible mixture through said passage, a fuel supply chamber, means for supplying fuel to said passage, an accelerator pump actuated by said throttle and operable to supply additional fuel on opening movements of the throttle to enrich the mixture for acceleration, said pump comprising a cylinder adapted to receive fuel from said fuel supply chamber and a piston slideable in said cylinder, means for preventing any accumulation of fuel vapor in said cylinder comprising a passage extending through the pump piston, said passage terminating in a downwardly opening conical portion, a valve coacting with said conical portion to control flow through the passage, a cage carried by said pump piston and comprising an elongated open-ended tubular member and a plurality of ribs supporting the tubular member in coaxially spaced relation with the conical portion of said passage, said valve means being normally seated upon said tubular member permitting fuel vapor to pass around said ribs and through said passage, fluid in the tubular member being adapted to move said valve means to seat within said conical portion of said passage to prevent fluid flow therethrough during the pumping stroke of said piston.
2. In a carburetor having a mixture passage, a throttle controlling the flow of combustible mixture through said passage, a fuel supply chamber, means for supplying fuel to said passage, an accelerator pump actuated by said throttle and operable to supply additional fuel on opening movements of the throttle to enrich the mixture for acceleration, said pump comprising a cylinder adapted to receive fuel from said fuel supply chamber and a piston slideable in said cylinder, means for preventing any accumulation of fuel vapor in said cylinder comprising a passage extending through the pump piston, said pas-

sage terminating in a downwardly opening conical portion, a ball valve coating with said conical portion to control flow through the passage, a cage carried by said pump piston and comprising an elongated open-ended tubular member and a plurality of ribs supporting the tubular member in coaxially spaced relation with the conical portion of said passage, a seat for said ball valve formed in the end of said tubular member adjacent said conical portion, said ball valve normally positioned on said seat permitting fuel vapor to pass around said ribs and through said passage, fluid in the tubular member

being adapted to move said valve means to seat within said conical portion of said passage to prevent fluid flow therethrough during the pumping stroke of said piston.
